Primary Examiner — George D. Kirschbaum*Assistant Examiner* — Maria J Edwards(74) *Attorney, Agent, or Firm* — Edgar A. Zarins; Nirav D. Parikh(57) **CLAIM**

The ornamental design for a pull, as shown and described.

DESCRIPTION

FIG. 1 is a perspective view of a pull showing my new design;

FIG. 2 is a top plan view thereof, the bottom view being a mirror image of the side shown;

FIG. 3 is a front elevational view thereof;

FIG. 4 is a rear view thereof; and,

FIG. 5 is a right end view thereof, the opposite end being a mirror image of the end shown.

The broken lines in the drawings illustrate portions of the article and form no part of the claimed design.

1 Claim, 1 Drawing Sheet(56)
